UNITED STATES PATENT OFFICE

CHARLES H. MCCOY, OF LOS ANGELES, CALIFORNIA

HAIR-WAVING APPARATUS

Application filed December 20, 1928. Serial No. 327,315.

My invention relates to a hair waving apparatus of the same general type disclosed in my copending application for United States Letters Patent filed December 13, 1927, Serial Number 239,632, and the principal object of my present invention is to generally improve upon and simplify the construction of the hair waving apparatus disclosed in my aforesaid copending application, as well as other existing forms of similar devices.

Further objects of my invention are to provide a hair waving apparatus that is comparatively light in weight and extremely flexible in construction in order that it will readily conform to the head, further to provide in a hair waving apparatus a plurality of sets of combs, each set including two combs, one of which is mounted for longitudinal movement upon the other, and both combs of each set being provided with curved teeth that are effective in engaging and holding the hair while the same is being waved, and, further to provide simple and efficient means for actuating the movable combs upon the fixed or stationary combs.

Further objects of my invention are to provide a hair waving apparatus that may be readily adjusted in size so as to be easily and conveniently fitted onto heads of different sizes, and further to provide simple means for securing the adjustable parts of the apparatus after the same have been properly positioned upon the head for use.

With the foregoing and other objects in view, my invention consists in certain novel features of construction and arrangement of parts that will hereinafter be more fully described and claimed and illustrated in the accompanying drawings, in which—

Fig. 1 is a top plan view of a hair waving apparatus constructed in accordance with my invention.

Fig. 2 is a side elevational view of the apparatus.

Fig. 3 is a perspective view of the hair waving apparatus in position upon the head.

Fig. 4 is an enlarged cross section taken on the line 4—4 of Fig. 1.

Fig. 5 is an enlarged top plan view of a

pair of flexible hair-engaging combs forming a part of the apparatus.

Fig. 6 is an elevational view of the front portion of the apparatus and showing the adjustably connected ends of the fixed or immovable combs.

Fig. 7 is a vertical section taken on the line 7—7 of Fig. 6.

Fig. 8 is a diagrammatic sectional view showing the teeth of the combs in the hair before the movable combs are actuated to wave the hair.

Fig. 9 is a diagrammatic sectional view showing the position of the movable combs after the same have been shifted to produce the waves in the hair.

Fig. 10 is a plan view of a modified form of one of the combs.

Fig. 11 is a plan view of modified form of the combs and with the teeth thereof open for the reception of the hair.

Fig. 12 is a plan view of the modified form of combs and showing the teeth thereof closed for engaging and holding the hair.

In the construction of my improved hair waving apparatus I make use of a frame that includes four pairs of combs, each pair comprising one comb that is stationary and the other comb of the pair being mounted so as to move for a limited distance longitudinally of the fixed comb.

Three of the pairs of combs are practically identical in construction, although differing slightly in size, in order to conform to the shape of the upper portion of the head, and the fourth pair of combs being disposed above the other three pairs so as to engage and wave that portion of the hair on top of the head to the side of the part or dividing line of the hair.

The three pairs of combs that pass around the head are generally designated by the characters A, B and C while the fourth pair of combs that are adapted to engage the hair on top of the head are designated by the reference character D.

Inasmuch as the pairs of combs A, B and C are practically identical in construction, only one pair will be described in detail.

Each of the pair of combs A, B and C in-

cludes an outer member 10, preferably formed of thin light weight metal, having a certain degree of resiliency, for instance German silver or aluminum, and the main body portion of this outer or stationary comb is substantially horse-shoe shaped in order to fit around the head just above the ears.

The pair of combs B occupy a plane a short distance above the pair of combs A and the 10 pair of combs C occupy a plane a short distance above the pair of combs B.

The three sets of combs are firmly secured to each other and maintained in spaced relation by vertically disposed straps 11 of metal 15 that are riveted or spot welded to the outer or fixed members of the pairs of combs, and the portions of these straps between the points where they are secured to the outer or fixed combs are bent outwardly, as designated by 12, in order to provide clearance for the 20 hair that is engaged by the teeth of the combs when the apparatus is in use.

At the front of the apparatus portions 13 of the metal straps forming the outer combs 25 are bent outwardly into diverging planes, and from the outer ends of said diverging portions the terminal portions of the metal straps are bent inwardly toward each other so as to form straight overlapping arms 14 which, when the 30 apparatus is applied to the head, occupy a position directly in front of the forehead.

Each pair of overlapping arms 14 passes beneath keepers 15 that are secured on the front face of a vertically disposed plate 16 35 and secured to the inner face of said plate and projecting rearwardly therefrom are pins 17 that carry at their rear ends a transversely curved plate 18 that is adapted to rest directly upon the central portion of the forehead 40 of the person to whom the apparatus is applied.

The upper edges of the overlapping arms 14 are provided with oppositely disposed notches 20, which latter are adapted to receive 45 spring detents or catches 21 that are secured to the rear face of the plate 16, and which project forwardly through apertures 22 in said plate and in the keepers 15.

The outer forward ends of the detents or 50 latches are provided with heads 23 that may be engaged to lift said detents when it is desired to release the overlapping arms 14.

The upper edge of each outer or stationary comb body 10 carries a series of horizontally 55 disposed laterally curved teeth 29 that are connected to the upper edge of the body 10 by short horizontally disposed U-shaped portions 30, which latter project outwardly and thence inwardly from the vertical plane occupied by the comb body 10.

Fixed to and projecting outwardly from the side portions of the fixed stationary combs 10 are short arms or brackets 31 that are adapted to be engaged by the thumb or fingers 60 when the movable combs are shifted longi-

tudinally upon the outer or stationary combs.

Arranged for longitudinal sliding movement upon the inner face of each stationary or outer comb body 10 is the body portion 32 of the inner or movable comb, the latter being formed from thin sheet metal having a certain degree of resiliency and the width of which inner comb body is substantially less than the width of the outer or fixed comb body 10.

Formed integral with and projecting inwardly from the upper edge of each movable comb body 32 is a series of horizontally disposed comb teeth 33 that occupies a plane parallel with and slightly below the plane occupied by the adjacent teeth 29 on the stationary comb.

The teeth 33 on the movable comb are curved in a direction opposite to that in which the teeth 29 are curved, and as a result of this oppositely arranged curvature of the two sets of teeth the hair when acted upon by the teeth of the moving comb will be automatically forced outwardly between the horizontally disposed U-shaped portions 30 of the teeth of the stationary combs. The two sets of teeth 29 and 33 project laterally in the same direction from the supporting members 10 and 32 and said two sets of teeth are spaced apart or arranged in different planes, as illustrated in Fig. 4, but as above stated, the teeth in one set are curved in one direction while the teeth in the other set are curved in the other direction (see Fig. 5).

Fixed in any suitable manner to the body 32 of each movable comb are the inner ends of pins 34, which pins project outwardly through longitudinally disposed inclined slots 35 that are formed in the body 10 of the stationary comb. These inclined slots are located adjacent to and in front of the arms or brackets 31 that project from the sides of the stationary combs, and carried by the outer ends of said pins 34 are plates 36 that are adapted to be engaged by the thumb or fingers during the manipulation of the movable combs.

A third set of pins 34 and inclined slots 35 are arranged between the rear portions of each pair of fixed and movable combs as illustrated in Fig. 2, and as a result of this arrangement each inner or movable comb will, as it is moved longitudinally relative to the outer or fixed comb, move vertically thereupon so that the teeth 33 will move toward or away from the teeth 29, depending upon the direction of movement of the inner comb.

Obviously the slots 35 are all inclined in the same direction so that all portions of the inner or movable comb will, when moved longitudinally, move simultaneously toward or away from the teeth 29 of the outer or fixed combs.

The pair of combs D which are relatively 130

short so as to extend lengthwise over the top of the head in a position substantially parallel with the part or division line of the hair are supported above the right hand portion of the upper pair of combs C by upright straps or frames 37 that are bowed outwardly between the combs C and D, as illustrated in Figs. 2 and 4.

The upper set of combs comprises a longitudinally curved metal strap 38 provided on its upper edge with a series of inwardly projecting laterally curved teeth 39, and arranged for longitudinal sliding movement against the inner face of the body of the fixed comb 38 is the body 40 of a movable comb, and which latter is provided on its upper edge with a series of inwardly projecting teeth 41 that occupy a plane just below and parallel with the plane occupied by the teeth 39.

The teeth 39 and 41 of this upper pair of combs are curved laterally in opposite directions so as to correspond with the curved arrangement of the teeth on the pairs of combs A, B and C.

Projecting from the movable comb body 40 through longitudinally disposed inclined slots 42 that are formed in comb body 38, are pins 43 carrying on their outer portions thumb or finger plates 44, and fixed to and projecting outwardly from the central portion of comb body 38 between the slots 42 is a thumb or finger plate 45.

In the use of my improved hair waving apparatus the latches 21 are disengaged from the pairs of overlapping arms 14 so as to permit said arms to be spread apart, thereby opening the pairs of combs A, B and C and the apparatus is now placed on the head directly over the hair, which latter has previously been moistened to the desired degree.

Before placing the apparatus on the head as just described, all of the movable combs are shifted longitudinally upon the fixed or stationary combs so that the teeth of said movable combs are at the limits of their movement away from the teeth of the fixed combs and which arrangement is graphically illustrated in Fig. 8.

As the apparatus is placed upon the head the teeth of the various combs will pass through the hair and rest upon the scalp and to secure the apparatus in proper position upon the head the overlapping arms 14 are now moved toward each other to contract the horse-shoe shaped pairs of combs and the forward portions of the pairs of combs are retained in their adjusted positions by the engagement of the detents or latching members 21 in coinciding pairs of the notches 20.

Thus when the apparatus is applied for use it fits snugly upon the head with the plate 18 resting against the central portion of the forehead and with the upper pair of combs D overlying the hair on top of the

head to the side of the part or dividing line of the hair.

The operator now shifts the movable combs longitudinally of the fixed or stationary combs by proper manipulation of the movable thumb or finger plates 36 and 44 and as the pins that carry said plates travel upwardly to the uppermost portions of the inclined slots 35 and 42 the engaged hair will be shifted into inclined or waved positions between the sets of combs as illustrated in Fig. 9 and the hair will be clamped in such position by the teeth of the movable combs as said teeth are brought into juxtaposition with the teeth of the fixed or stationary combs.

As the teeth of the movable combs move past the teeth of the stationary comb, the hair engaged between said teeth will be gradually forced outwardly into the U-shaped portions 30 of the fixed combs, due to the opposite curvature or inclination of the teeth of the fixed and movable combs, and thus when the movable combs have been shifted to their limit of movement relative to the fixed combs the hair will be practically locked between the teeth of the various sets of combs.

After the movable combs have been shifted as just described to produce the waves in the engaged hair, a mild degree of heat may be applied to the apparatus or to the hair to dry the same and after the drying operation the movable combs are shifted to their original positions so as to permit the apparatus to be removed from the head.

The movement of the movable combs away from the fixed combs enables the teeth of all of the combs to be readily disengaged from the hair, and thus the same is left in the desired waved condition.

In Figs. 10, 11 and 12 I have illustrated forms of combs wherein the teeth are provided on their ends with lateral projections, the same being designated by the numeral 46, and where such construction is employed and the combs are arranged so that the projections on one comb extend in a direction opposite to the projections of the other comb, the strands of hair that engage between the comb teeth are effectually retained when the movable comb is shifted a short distance upon the fixed or immovable comb.

Thus it will be seen that I have provided a hair waving apparatus that is relatively simple in construction, inexpensive of manufacture, and very effective in performing the functions for which it is intended.

The entire apparatus is comparatively light in weight, capable of being easily and quickly applied for use, and by a comparatively short movement of the movable combs upon the fixed or stationary combs the desired results are produced.

It will be understood that minor changes

in the size, form and construction of the various parts of my improved hair waving apparatus may be made and substituted for those herein shown and described without departing from the spirit of my invention, 5 the scope of which is set forth in the appended claims.

I claim as my invention:

1. In a hair waving apparatus, a plurality 10 of pairs of horse-shoe shaped combs, each pair comprising a relatively stationary comb and a movable comb, said pairs of combs being arranged one above the other and the teeth of which combs project inwardly from the upper edges of the bodies of the combs.

2. In a hair waving apparatus, a plurality 20 of pairs of horse-shoe shaped combs, each pair comprising a relatively stationary comb and a movable comb, said pairs of combs being arranged one above the other, the teeth of which combs project inwardly from the upper edges of the bodies of the combs, and adjustable means connecting the ends of the respective pairs of combs.

25 3. In a hair waving apparatus, a plurality of pairs of horse-shoe shaped combs, each pair comprising a relatively stationary comb and a movable comb, said pairs of combs being arranged one above the other, the teeth of which combs project inwardly from the upper edges of the bodies of the combs, the teeth on one comb of each pair being curved in one direction and the teeth on the other comb of each pair being curved in the opposite direction.

40 4. In a hair waving apparatus, a pair of horse-shoe shaped combs one of which is mounted for sliding movement upon the other, means for moving the sliding combs upon the other, adjustable means connecting the ends of said combs, the teeth of which combs project inwardly from the upper edges of the bodies of said combs, the teeth on one comb being curved in one direction and the teeth on the other comb being curved in the other direction.

45 5. In a hair waving apparatus, a plurality of pairs of horse-shoe shaped combs, each pair comprising a relatively stationary comb, 50 and a comb mounted for sliding movement on said stationary comb, said pairs of combs being arranged one above the other with the teeth of said combs projecting inwardly from the upper edges of the bodies of the combs, and a pair of curved combs supported above the uppermost pair of horse-shoe shaped combs, one of which curved combs is mounted for sliding movement upon the other.

60 6. In a hair waving apparatus, a pair of horse-shoe shaped combs, each formed in a single piece, the inner one of which combs is mounted for sliding movement upon the other, the teeth of which combs project inwardly from the upper edges of the comb

bodies and the two sets of teeth occupying different horizontal planes.

7. In a hair waving apparatus, a pair of horse-shoe shaped combs, each formed in a single piece, the inner one of which combs is mounted for sliding movement upon the other, the teeth of which combs project inwardly from the upper edges of the comb bodies, the two sets of teeth occupying different horizontal planes, one set of teeth being curved in one direction and the other set of teeth being curved in the other direction.

75 8. In a hair waving apparatus, a pair of horse-shoe shaped combs, each formed in a single piece, one of which combs is mounted for sliding movement upon the other, the teeth of which combs project inwardly from the upper edges of the comb bodies and the teeth of one of said combs being connected to the comb body by horizontally disposed U-shaped portions.

80 9. In a hair waving apparatus, a pair of horse-shoe shaped combs, each formed in a single piece, one of which combs is mounted for sliding movement upon the other, the teeth of which combs project inwardly from the upper edges of the comb bodies, the teeth of one of said combs being connected to the comb body by horizontally disposed U-shaped portions, the teeth on one comb being curved in one direction and the teeth in the other comb being curved in the other direction.

85 10. In a hair waving apparatus, a plurality of pairs of combs, one comb of each pair being mounted for sliding movement upon the other, the teeth of which combs project inwardly from the upper edges of the comb bodies and independent means for adjustably connecting the ends of the respective pairs of combs.

In testimony whereof I affix my signature.
CHARLES H. McCOY.
